[57] CLAIM

The ornamental design for a bottle, as shown and described.

DESCRIPTION

FIG. 1 is front elevation of a bottle showing my new design, the rear elevation being the same;

FIG. 2 is a right side elevation thereof, the left side elevation being the same;

FIG. 3 is a horizontal cross sectional view taken along line A—A of FIGS. 1 and 2;

FIG. 4 is a top plan view thereof;

FIG. 5 is a front elevation of a second embodiment of the bottle, the rear elevation being the same;

FIG. 6 is a right side elevation of the second embodiment, the left side elevation being the same;

FIG. 7 is a horizontal cross sectional view of the second embodiment taken along line B—B in FIGS. 5 and 6; and, FIG. 8 is a top plan view of the second embodiment.

The broken line showing of a bottle neck and bottom part is for illustrative purposes only and forms no part of the claimed design.
